UNITED STATES PATENT OFFICE.

JOHN HOLTZMAN, OF NEW YORK, N. Y.

CLEANING DEVICE.

Application filed November 23, 1921. Serial No. 517,409.

This invention relates to a cleaning device, more particularly to a revolving brush mechanism with means for feeding water and soap or other cleaning fluid in proper proportions to the brush.

One feature consists in the means for revolving the brush to give to the surface or body to which it is applied a slight massaging effect, and at the same time to be free to move the brush to any position over the body to be cleaned. Another feature of the invention comprises means for feeding water and a cleaning fluid in suitable proportions to the brush. The invention may be used for cleaning different objects and among which may be mentioned glasses that are used in public places for instance those for soda water stands and the like, the invention may also be used for massaging the scalp and skin of the user.

Referring to the drawings, Fig. 1 shows an elevation of the cleaning device, partly in vertical axial section, and Fig. 2 shows a bottom plan view of a detail.

Referring now to Figs. 1 and 2, the brush preferably consists of a rubber plate with fingers 2 and holes 3 constituting a rubber brush. A concaved holding plate 5 is indicated with the holes 4 and the nipple 6, which latter is inclined to the normal axis of said plate. The rubber plate 1 is detachably supported or fastened to the holding plate 5 and the holes 4 register with the holes 3. A container 7 for cleaning material is detachably fastened at its lower end to the nipple 6 and its upper end to the revolving hollow shaft 8. The latter is supported in the ball bearings of the water container 10. The water container 10 is provided with the bottom plate 11 having a plurality of holes 12 through which the water may flow to the holding plate 5. The water may be supplied through a flexible hose 13, attached at the hollow handle 14' of the water container 10. To provide proper bearings for the rotating shaft 8 in addition to the ball-bearings 9, a projection 14 on the cleaning fluid container 7 is detachably supported in a bearing 15 in the center of the cover 11.

The means for revolving the shaft 8 consists of the electric motor 16 fastened to a suitable support such as a wall 17. The shaft of this motor is coupled by means of worm gears in the housing 18 to a flexible shaft 19 enclosed in the flexible hose 20.

The latter is connected at its end to the housing 18 and at its bottom end is the sleeve 48 at which latter point the flexible shaft 19 is coupled to the rotatable shaft 8. The outline of an electric switch is shown with the pull socket 22.

A flexible cord 23 on the reel 24, has one end fastened to any suitable support near the motor. The flexible cord 23 is wound on the reel 24, by means of the handle 25 and to one end is attached the plug 26, that may be secured to any convenient lamp socket or similar outlet.

The cleaning fluid dispensing means is provided with a valve 30, which may be closed by hand over the opening 31, coating with the air inlet 32 in the shaft 8, at such times when the flow of the liquid from the container 7 is not desired. When the air can enter the shaft the fluid in the container 7 drops by gravity.

The operation of this mechanism is as follows:

The container 7 may be filled with cleaning fluid through the opening 35 in the nipple 6. When the motor 16 is started the water is caused to flow from the supply into the container 10 and from the latter through the holes 12 and over the plate 5. The water then flows through the holes 4 and over the edges of the brush 1 on to the body to be cleaned. Sufficient cleaning fluid will at the same time be dispensed through the opening 35 to mix with the water and produce a suitable lather. When sufficient fluid has been supplied, the closing of valve 30 will stop the flow due to the shutting off of the air supply through the inlet 32. The holding plate 5 may be detached from the bottom plate 11, so that the cleaning device may be used without said plate 5 and its rubber brush. In this case the water flowing from the holes 12 can be directly directed to the body of the user.

Having thus described my invention, what I claim as new and desire to secure by Letters Patent, is:—

1. In a cleaning device the combination of a container having holes for the discharge of a fluid, means to discharge the container with the fluid, a second container rotatably mounted within the first container, a tubular brush below the first container, and connecting means between said brush and the second container for rotating the brush with the second container.

2

2. In a cleaning device the combination of a container having holes for the discharge of a fluid, means to charge the container with the fluid, a soap container rotatably mounted within the first named container, a pipe extending from the soap container through one end of the first named container, a vent valve device for said pipe, a holding plate below the first container and connected 10 to the soap container, a brush connected to said plate and means to rotate said pipe.

3. In a cleaning device the combination of a water container having holes for the discharge of water, means to feed water to the container, a container for a cleaning fluid within the water container, a hollow shaft connected to the inner container and extending through one end of the water container with its axis in alignment with the 20 axis of the water container, a holding plate below the water container, a nipple extending from the holding plate and inclined to its normal axis, said nipple extending into the water container and connected to the inner container, a brush connected to the holding plate and means to turn the hollow shaft.

4. In a cleaning device the combination of

a water container having a bottom cover plate provided with holes, a holding plate 30 with a nipple extending therefrom, said nipple rotatably and detachably connected to said cover plate and extending into the container, a brush having flexible fingers detachably connected to said holding plate, means to rotate said holding plate with its brush, means to feed water to said container and means to feed a cleaning fluid to said brush.

5. In a cleaning device the combination of 40 a water container having a bottom plate provided with holes, a holding plate having a nipple, said nipple extending through the bottom plate of the water container, a brush with flexible fingers connected to said holding plate, means to feed water to the water container, a hollow shaft extending into said container, a second container for a cleaning fluid in said water container connected to said hollow shaft, the nipple of the holding plate connected to said second container and means to turn said hollow shaft.

In testimony whereof I have signed my name to this specification.

JOHN HOLTZMAN.
